UNITED STATES PATENT OFFICE.

HARRY G. HAWEKOTTE AND HENRY W. KLAUSMANN, OF INDIANAPOLIS, INDIANA.

TOY AERIAL SWING.

No. 872,511.

Specification of Letters Patent.

Patented Dec. 3, 1907.

Application filed September 14, 1906. Serial No. 334,578.

To all whom it may concern:

Be it known that we, HARRY G. HAWEKOTTE and HENRY W. KLAUSMANN, citizens of the United States, residing at Indianapolis, in the county of Marion and State of Indiana, have invented certain new and useful Improvements in Toy Aerial Swings; and we do declare the following to be a full, clear, and exact description of the invention, reference being had to the accompanying drawings, and to the letters and figures of reference marked thereon, which form a part of this specification.

This invention relates to portable operative mechanical apparatus and mechanism which may be constructed in various sizes, but is particularly adapted to be constructed in suitable sizes to be used as toys, both for entertainment and instruction, and the invention has reference more particularly to self-contained mechanical apparatus in which the power for operating the mechanism is developed by means of parts of the apparatus.

The objects of the invention are to provide an attractive entertaining toy adapted to be operated at a low rate of expense for power, and to provide particularly an aerial swing of such construction as to be adapted to be knocked down, either for shipment, for transferring from place to place, or for convenience in storing the toy, a still further object being to provide an electromagnetically operated aerial swing, adapted to be operated with the least amount of electric current.

With the above-mentioned and minor objects in view, the invention consists in a toy aerial swing comprising a rotative vertical shaft, and guides therefor, folding arms mounted on the shaft and supporting a plurality of swings, an electro magnetic motor, a platform for supporting the motor and apparatus, a battery for the motor and a musical instrument connected with the motor, and the invention consists further in the novel parts and the combinations and arrangements of parts as hereinafter particularly described and claimed.

Referring to the drawings, Figure 1 is a front elevation of the complete toy or apparatus, constructed substantially in accordance with the invention; Fig. 2, a top plan thereof; Fig. 3, a fragmentary side elevation showing the lower portions of the toy, parts of the musical instrument in the form of a music box being broken away; Fig. 4, a frag-

mentary elevation of the side opposite to that shown in the preceding figure; Fig. 5, a fragmentary horizontal sectional view approximately at the plane of the line A—A, in Fig. 1; Fig. 6, a fragmentary vertical sectional view approximately on the plane of the line B in Fig. 5; Fig. 7, a fragmentary vertical sectional view approximately on the line C in Fig. 6; Fig. 8, a fragmentary vertical sectional view approximately on the line D in Fig. 5; Fig. 9, a fragmentary detail view showing the manner of connecting different parts of the platform of the apparatus; Fig. 10, a fragmentary horizontal sectional view approximately on the line E—E in Fig. 1; Fig. 11, a plan view of the apparatus inverted with the bottom of the battery case broken away; and, Fig. 12, a fragmentary sectional view approximately on the line F—F in Fig. 3.

Similar reference characters in the several figures of the drawings, designate corresponding elements or features of construction.

In the practical embodiment of the invention, suitable metals are usually employed in the manufacture of the various parts wherever found convenient, and the swing apparatus is so designed that it may be operated when desired by other means than that comprised in the invention, the motor and battery herein described however, being most desirable in order that the toy may be complete and compact in itself.

The invention comprises a circular platform which is composed of a central main section G, square in plan and having at the under side of each corner thereof a lug a to which a leg b is attached for supporting the whole apparatus, and four sections H, H', 95 H², H³, all attached removably to the main section and joined thereto at the sides thereof, each side of the main section having two openings c and c' therein, and two bearings d and d', that are lower than the top of the main section, each removable section having a pair of projections e and e' attached thereto and adapted to enter the said openings and to engage the tops of the bearings and extend under and engage the under side of the main section so that when the platform is complete the tops of all of the sections are flush or in one and the same plane. The removable sections may be disconnected from the main section by elevating their free ends and 110

- 10 withdrawing the projections thereof from the openings of the main section. Each removable section has a suitable number of posts *f* attached to the top at the peripheral edge 5 thereof, and a curved railing *g* is attached to the posts so that when the parts are assembled the platform will have a circular railing extending on its top along the periphery thereof.
- 15 10 A suitable tower is mounted on the main section of the platform and preferably comprises four posts *I*, *I'*, *I²*, *I³*, attached to the corner portions of the section in slanting arrangement, the tops of the posts being connected together by a cap piece *h*. The posts are provided with suitable braces and a roof *i* is supported by the posts at a suitable distance above the platform, leaving space under the roof for the motor.
- 20 15 The electro magnetic motor is mounted on the middle portion of the main section of the platform and preferably comprises a frame having a base *j* and two side members *k* and *k'*, there being a suitable number of electro 25 magnet windings *l*, on cores suitably connected together and mounted on the base between the side members of the frame, and an armature *m*, having an opening 13 therein, the armature arranged being above the 30 cores and connected at one end thereof by a pivot *n* to the side members of the frame. A rotative shaft *o*, having a crank *p*, is mounted in the side members of the frame and a pitman *q* connects the free end of the 35 armature with the crank, said shaft having a grooved pulley *r* secured thereto between the frame members *k* and *k'*, and a grooved pulley *s*, secured to the shaft outside of one 40 of the frame members. Also a cam *t* is secured to the rotative shaft to form a part of the make-and-break device for magnetizing and de-magnetizing the magnet cores, the windings of the cores being suitably connected with a part of the motor frame as will 45 be understood. Another part of the make-and-break device comprises a contact arm *u* which is pivoted between its ends to an insulator *u'*, by a pivot 14, one end of the arm being elastic and arranged opposite to the 50 cam *t*, the other end of the arm extending through an opening in the main section *G* of the platform and being connected by a screw 55 15, working in an insulated nut *v'*, that is carried by the arm, the screw being mounted in a journal support 16 which is attached to the main section of the platform. An operating stem *v* is connected by a knuckle 17, to the screw 15, the outer end of the stem being supported and guided in a hook bearing 18, which is attached to the removable 60 section *H* of the platform so that the stem may be disconnected from the hook-support and swung around as indicated in Fig. 11, when it is desired to disconnect the section *H* from the main section of the platform.

A case 19 is attached to the under side of the main section *G*, and supports a suitable number of batteries (preferably dry batteries,) as 20 and 21, connected together by a circuit wire and suitably connected with the 70 windings of the electro magnets, one of the batteries being connected by a wire 22 to the arm *u*.

The base *j* of the motor frame is provided with a socket bearing 23, in which a vertical shaft *J*, having a conical bearing 24, is rotatively supported, the shaft extending through the opening 13, and a grooved pulley *w* is secured to the shaft and connected by a belt *x*, to the pulley *r*, of the main shaft. A ring *y* is secured to the upper portion of the shaft *J*, above the cap *h*, which guides the upper end of the shaft. A suitable number of arms 25 are connected by pivots 26 to the ring *y*, and are adapted to fold against the tower as 85 indicated by dotted lines in Fig. 1, the arms being normally held in horizontal positions by means of a collar 27, that is secured to the top of the shaft and links 28 hooked into the collar and to the arms. A suitable number 90 of cars *K*, or the like are suspended by means of links or cords 29, to the outer ends of the arms 25, the cars being adapted to swing outwardly by centrifugal force when the shaft *J* rotates.

95 A mechanical musical instrument *L* is mounted on the main section *G* of the platform adjacent to the motor, and the instrument may be variously constructed, it being provided with an operating pulley 30 connected by a belt 31 to the pulley *s* of the main shaft.

100 It should be understood that in lieu of the cars *K*, various other carriers may be substituted, it being designed to place dolls and various images, in the cars or on the carriers, for amusement purposes.

105 In practical use, when the apparatus is not in operation the contact part of the arm *u* will be held out of reach of the cam *t*, and in 110 order to start the motor, the stem *v* is to be rotated so as to move the arm *u* about its pivot to bring the contact part thereof within reach of the cam, then the main shaft *o* may be turned slightly so as to make contact and energize the electro magnet, when the motor 115 will begin to operate and continue by reason of the electro magnets periodically attracting the armature *m*, and the speed of the motor may be regulated by manipulating the stem *v*, so as to effect a longer or shorter period of contact between the cam *t* and the contact end of the arm *u*, as may be desired. The motor will rotate the shaft *J* and thereby 120 swing the cars *K* in a circle above the platform, as will be understood.

125 Having thus described the invention what is claimed as new is—

1. An aerial swing including a platform, an electro-magnetic motor mounted upon the 130

- platform and having an armature provided with an opening therein, a battery, electrical connections between the battery and the motor, a tower mounted on the platform, a vertical shaft mounted in the tower and extending through the opening in the armature to the base of the motor and supported thereon, operative connections between the motor and the shaft, arms mounted on the shaft, 10 and swings supported by the arms.
2. An aerial swing including a platform comprising a main section, supporting legs attached to the main section, and a plurality of platform sections attached removably to 15 the main section; a motor mounted on the main section of the platform, a battery mounted under and supported by the main section of the platform, a tower mounted on the main section of the platform, a vertical 20 shaft mounted in the tower and having a pulley, a belt connecting the pulley and the motor, and a controlling device for the motor having an operating stem extending under one of the plurality of platform sections and 25 detachably connected therewith.
3. An aerial swing including a platform comprising a main section having supporting legs, and a plurality of portable sections attached removably to the main section and 30 provided on the tops thereof with posts having railings attached thereto; a tower mounted on the main section of the platform, a vertical shaft mounted rotatively in the tower and having a ring attached thereto, a plurality 35 of arms pivoted to the ring, swings supported by the arms, and means for rotating the vertical shaft.
4. An aerial swing including a platform comprising a main section provided with supporting legs and having a case attached to the under side thereof and a tower attached to the top thereof, and a plurality of portable sections attached removably to the main section; a motor mounted on the main section 45 of the platform, a battery supported by said case, a vertical shaft mounted in the tower and connected with the motor, arms mounted on the vertical shaft, and swings supported by the arms.
5. An aerial swing including a platform having removable side sections, a motor mounted on the platform, railings mounted on the removable sections of the platform, a tower mounted on the platform over the motor and having a roof attached thereto covering the motor, a battery mounted under the platform below the motor, an electrical circuit between the battery and the motor and having make-and-break devices connected therewith, a folding operating device connected with the make-and-break devices, a vertical shaft mounted in the tower and connected with the motor, arms mounted on the shaft, and swings supported by the arms.
6. An aerial swing comprising a platform 65 having a tower attached to the top thereof and a case attached to the bottom thereof, an electro-magnetic motor mounted on the platform and comprising magnet cores, an apertured armature supported pivotally above the cores, a rotative crank-shaft, a pitman connected to the armature and also to the crank-shaft, and make-and-break devices; a battery supported in the case beneath the platform and connected with the make-and-break devices, a vertical shaft mounted in the tower and connected with the crank-shaft of the motor, the shaft extending through the aperture of the armature, arms pivotally supported by the vertical shaft, 70 swings supported by the arms, and links connected to the arms and also to the vertical shaft.
7. An aerial swing including a portable platform, a tower mounted on the platform, a vertical shaft mounted in the tower rotatively and having a ring and a collar secured thereto above the tower, arms pivoted to the ring, swings supported by the arms, hook links connected to the arms and also to the 75 collar, a drive wheel secured to the shaft, and a motor connected with the drive wheel.
8. An aerial swing including a portable platform having a tower attached to the top thereof and a case attached to the bottom thereof, an electro-magnetic motor mounted upon the platform, a battery supported in the case beneath the platform, circuit wires between the battery and the motor, make-and-break devices for the circuit wires, a vertical shaft mounted in the tower rotatively and connected operatively with the motor, arms mounted on the shaft, and swings supported by the arms.
9. An aerial swing including a platform 85 having a tower attached to the top thereof and a battery case attached to the bottom thereof, a motor mounted on the platform, a battery supported in the case beneath the platform, circuit-wires between the battery and the motor, a vertical shaft mounted in the tower rotatively and connected operatively with the motor, a ring secured to the shaft above the 90 ring, arms pivoted to the ring, links connected to the arms and also to the collar, and swings supported by the arms.
10. An aerial swing including a main platform section, a plurality of platform sections attached removably to the main platform section, a motor mounted on the main section of the platform, a battery, electrical connections between the battery and the motor, a tower mounted on the main section of the platform, a vertical rotative shaft mounted 100 in the tower and connected operatively with the motor, arms mounted on the shaft, swings supported by the arms, and a controlling device for making and breaking the electrical connections and having an operating stem 105

extending under one of the removable sections of the platform and detachably connected therewith.

11. An aerial swing comprising a platform having a tower attached to the top thereof and a case attached to the bottom thereof, an electro-magnetic motor mounted on the platform and having a plurality of drive pulleys and make-and-break devices, a battery supported in the case beneath the platform and connected with the make-and-break devices, a musical instrument mounted on the platform adjacent to the motor and having a pulley in connection with one of the drive pulleys of the motor, a roof attached to the

tower and covering the motor and the musical instrument, a vertical rotative shaft mounted in the tower and extending through the roof, a pulley secured to the shaft and having operative connection with a drive 20 pulley of the motor, arms mounted on the vertical rotative shaft, and swings supported by the arms.

In testimony whereof, we affix our signatures in presence of two witnesses.

HARRY G. HAWEKOTTE.
HENRY W. KLAUSMANN.
